UNITED STATES PATENT OFFICE.

OTTO H. ESCHHOLZ, OF WILKINSBURG, PENNSYLVANIA, ASSIGNOR TO WESTINGHOUSE ELECTRIC & MANUFACTURING COMPANY, A CORPORATION OF PENNSYLVANIA.

ARC-EXTINGUISHING DEVICE.

Application filed February 20, 1922. Serial No. 537,856.

To all whom it may concern:

Be it known that I, OTTO H. ESCHHOLZ, a citizen of the United States, and a resident of Wilkinsburg, in the county of Allegheny and State of Pennsylvania, have invented a new and useful Improvement in Arc-Extinguishing Devices, of which the following is a specification.

My invention relates to arc-extinguishing devices for employment in connection with a pair of relatively movable electrical contact members and particularly to means whereby the re-establishment of arcs between a pair of relatively movable contact members shall be prevented and also to means whereby arcs may be completely extinguished.

Upon interrupting circuits of high voltage and the extinguishing of arcs formed between the interrupter contact members, re-establishment of the arcs frequently occurs, such re-establishment being facilitated by the energy developed in the region of the arc-ing or switch contact members. This action results in rapid deterioration of switch parts, excessive arc duration, and, in some cases, failure to clear the circuit.

Furthermore, it is recognized, that, upon quickly interrupting a highly inductive circuit, voltages may be developed that are considerably in excess of the circuit voltage. The desirability of rupturing such circuits without developing excessive voltage during the period of circuit-energy-dissipation is evident.

The object of my invention is to provide means whereby an arc formed between a pair of spaced conductor members may be readily extinguished and liability of arc re-establishment minimized.

In practicing my invention, I provide means whereby, after the rupture of an arc between a pair of main conductor members, another arc is permitted to form between a pair of auxiliary conductor members that are electrically connected to the main conductor members, and I provide, in addition, means for extinguishing the arcs that are formed between either, or both, of the pairs of conductor members.

In the accompanying drawings,

Figure 1 is a view, in front elevation of a portion of a circuit interrupter embodying my invention; and

Figs. 2 and 3 are views taken on the lines II—II and III—III, respectively, of Fig. 1. 55

A movable contact member 4 may be employed either as one of the main switch members or as an arc-ing tip supported by the main contact member of a circuit. The member 4 is movable with respect to a contact member 5 that is mounted upon a base 6 of insulating material, the contact members 4 and 5 being connected in a circuit (not shown).

The contact members 4 and 5 are provided with arc-ing horns 7 and are located in a chamber 8 that is provided with walls 9 of insulating material.

A second chamber 11 is mounted adjacent to the chamber 8 and is provided with insulating barriers 12 between which are mounted a pair of arc-ing horns 13 and 14. The arc-ing horn 13 is mounted upon a rigid support 15 and is connected to the movable contact member 4 by means of a flexible conductor 16. The arc-ing horn 14 is supported by the insulating base 6 and has electrical connection with the stationary contact member 5 by means of the member 18. A pair of blow-out coils 20 and 21 are provided at the rear of chambers 8 and 11 to co-operate with pole pieces 23 and 24 to rupture arcs that may be formed either between the arc-ing horns 13 and 14 or the horns of the contact members 4 and 5. 70

The arc-ing horn 13 is provided with a slot through which a screw 26 extends, so that it may have sliding adjustment upon its support 15. A set screw 27 determines the position of the horn 13 upon the supporting member 15, and, consequently, permits adjustment thereof with respect to the arc-ing horn 14 to vary the distance between the horns 13 and 14. Each of the horns 13 and 14 is provided with a protuberance 28. 75

Upon the separation of the contact members 4 and 5, an arc is formed therebetween. Under the influence of the magnetic blow-out coils, the arc stream rises and its terminals are caused to travel upwardly along the arc-ing horns 7 until the voltage developed across this arc stream equals the breakdown voltage of the gap between the protuberances 28 of the arc-ing horns 13 and 14. 90

An arc will thereby be established between the protuberances 28 of the arc-ing horns 13 and 14 because they are electrically con- 100

105

nected to the contact members 4 and 5, as heretofore explained, and the first arc will thereupon be extinguished.

The arc formed between portions 28 is 5 carried upwardly along the arcing horns 13 and 14 until it is finally extinguished by the magnetic blow-out devices heretofore described.

It will be observed that the protruding 10 portions 28 of the arcing horns 13 and 14 are relatively close together and this distance is purposely made less than the distance between the contact members 4 and 5 when the contact member 4 is in its open 15 position.

For this reason, an arc will form between the arcing horns 13 and 14, instead of being re-established between the contact members 4 and 5, and the contact members 4 and 5, as 20 well as the main arc-chute chamber, are thus protected against erosion by reason of excessive arcing.

The arcing horns 13 and 14 are made relatively adjustable so that the distance there- 25 between may be gauged to permit the formation of an arc at a predetermined voltage.

It will be understood that the chambers 30 8 and 11 may be mounted at a considerable distance apart, or that the two sets of arcing horns may be mounted in a single chamber. Also, the horns that are supported upon the contact members may be provided with protuberances and the auxiliary 35 horns dispensed with.

With the arc-forming gap so proportioned that it will break down at a predetermined voltage, re-ignition of arcs will occur thereacross more readily than be- 40 tween the separated contact members, and subsequent re-ignitions will serve to dissipate the stored circuit energy with a minimum of wear on the switch parts and will cease to occur when the arc-stream voltage 45 becomes less than that required to break down the gap, at which time the final interruption of the arc occurs.

Various other changes in detail or general arrangement may be made without departing from the spirit and scope of the 50 invention as defined in the accompanying claims.

I claim as my invention:

1. The combination with a pair of relatively movable contact members, of a pair of arcing horns located at a point removed from the contact members and spaced apart a distance less than the distance between the contact members when in fully-open position, and a blow-out device for rupturing arcs that form between the contact members and the arcing horns, the arcing horns having electrical connections to the contact members.

2. The combination with a pair of rela-

tively movable contact members, of means for extinguishing an arc therebetween comprising a pair of spaced arcing members having electrical connections to the movable contact members, means for causing the rupture of an arc formed between the movable contact members and for causing an arc to be established between the arcing horns, and means for extinguishing the arc formed between the arcing horns.

3. The combination with a pair of relatively movable contact members, of an arcing chamber therefor, an auxiliary arcing chamber, a pair of relatively-fixed spaced conductor members located in the said auxiliary chamber, and electrical connections between the movable contact members, and the said conductor members, the last named members being spaced apart a distance less than the distance between the movable contact members in their open position.

4. The combination with a pair of relatively movable contact members, of an arcing chamber therefor, an auxiliary arcing chamber, a pair of relatively-fixed spaced conductor members located in the said auxiliary chamber, a magnetic-blow-out device for extinguishing arcs formed between the movable contact members, and electrical connections between the movable contact members and the said conductor members, the last named members being spaced apart a distance less than the distance between the movable contact members in their open position.

5. The combination with a pair of spaced conductor members between which arcs may be formed, of a protective device there- 105 for comprising two auxiliary conductor members electrically connected to the first named members and spaced apart a less distance than the distance between the first named conductor members under predetermined conditions.

6. The combination with a plurality of 110 movable switch members, of a means for causing the rupture of an arc formed between the switch members comprising a pair of arcing horns connected in shunt relation to at least two of the switch members and spaced apart a distance less than the maximum distance of separation of the switch members when in open position.

7. The combination with a pair of relatively movable contact members, of a pair 120 of arcing horns connected to the contact members and located at a point removed from the contact members and spaced apart a distance less than the distance between the contact members when in fully open position.

In testimony whereof, I have hereunto 125 subscribed my name this 15th day of February, 1922.

OTTO H. ESCHHOLZ.
